UNITED STATES PATENT OFFICE.

JAMES A. SEYMOUR AND JOHN E. MCINTOSH, OF AUBURN, NEW YORK.

STEAM-ENGINE.

SPECIFICATION forming part of Letters Patent No. 402,622, dated May 7, 1889.

Application filed July 23, 1888. Serial No. 280,759. (No model.)

To all whom it may concern:

Be it known that we, JAMES A. SEYMOUR and JOHN E. MCINTOSH, of the city of Auburn, New York, have invented certain new and useful Improvements in Steam-Engines, of which the following is a description, reference being had to the accompanying drawings, forming part of this specification.

The figure shown is an elevation.

This invention consists in certain new constructions, arrangements, and combinations of the several parts of a compound steam-engine, whereby it is simplified, the action of the valve-operating mechanism is made direct, the operative parts are brought compactly together, and the efficiency of the engine is increased, while its cost is lessened by the resulting simplicity of construction.

Our invention relates to that class of compound engines which is commonly designated as "tandem" engines—that is, engines in which the high and low pressure cylinders are placed with their axes in line, so that both of their pistons may be secured upon and may actuate one piston-rod, the steam acting simultaneously and in the same direction upon both pistons. In such an engine we arrange the steam-chests of the high and low pressure cylinders upon opposite sides of their respective cylinders, and by this arrangement we are able to extend their respective valve-rods upon opposite sides of their common piston-rod toward a double-crank shaft placed in the same plane, but at right angles with the piston-rod. This double-crank shaft is then provided upon either side of the crank with an eccentric, and eccentric-rods being connected thereupon are attached at their other extremities to the aforesaid valve-rods, which are supported by suitable guides. By this

construction it will be seen that a tandem single-piston-rod compound engine has its valve-rods connected through their eccentric-rods to two eccentrics placed upon opposite sides of the crank-shaft, which is in the plane 45 of and at right angles to the piston-rod or axial line of the two cylinders. The valve-actuating parts are made in the most simple manner and of the most direct action, while the construction of the whole engine is made 50 very simple and of consequent cheapness.

In the drawing, A is the high-pressure cylinder; A', its steam-chest; a, its valve-rod; a', valve-rod guide; a², its eccentric-rod operated by the eccentric a³.

B is the low-pressure cylinder; B', its steam-chest; b, its valve-rod; b', its guide; b², its eccentric-rod operated by the eccentric b³.

The eccentrics a³ and b³ are both placed upon the double-crank shaft C D C.

Having thus described our invention, what we claim as new, and desire to secure by Letters Patent, is—

In a compound engine, the cylinders A and B, arranged in line axially and having their respective steam-chests A' and B' upon opposite sides thereof, in combination with the double-crank shaft C D C, which is provided with two eccentrics, a³ and b³, upon either side of the crank, respectively, said crank-shaft being in the plane of and at right angles to the axes of the cylinders A and B, and the valve-rods a and b, connected, respectively, to the eccentrics a³ and b³ through the eccentric-rods a² and b², substantially as described.

JAMES A. SEYMOUR.
JNO. E. MCINTOSH.

Correction in Letters Patent No. 402,622.

It is hereby certified that in Letters Patent No. 402,622, granted May 7, 1889, upon the application of James A. Seymour and John E. McIntosh, of Auburn, New York, for an improvement in "Steam Engines," an error appears in the printed specification requiring correction as follows: In line 9 the description of the drawing should read, *The figure shown is a plan view*, instead of "The figure shown is an elevation," and that the said Letters Patent should be read with this correction therein to make the same conform to the record of the case in the Patent Office.

Signed, countersigned, and sealed this 14th day of May, A. D. 1889.

[SEAL.]

CYRUS BUSSEY,
Assistant Secretary of the Interior.

Countersigned:

C. E. MITCHELL,
Commissioner of Patents.
